UNITED STATES PATENT OFFICE.

ETHEL A. WADE, OF SPRINGFIELD, MISSOURI.

SKIRT-MARKER.

1,271,394.

Specification of Letters Patent.

Patented July 2, 1918.

Application filed September 16, 1916. Serial No. 120,500.

To all whom it may concern:

Be it known that I, ETHEL A. WADE, a citizen of the United States, residing at Springfield, in the county of Greene and

5 State of Missouri, have invented certain new and useful Improvements in Skirt-Markers; and I do hereby declare the following to be a full, clear, and exact description of the invention, such as will enable others skilled 10 in the art to which it appertains to make and use the same.

This invention relates to improvements in that type of skirt marking device consisting of a hollow body in the form of the frustum 15 of a cone, having horizontal, concentric rows of gage lines to admit of the bottom line of a skirt being accurately obtained, and an object of the invention is the provision of a marker formed of flexible flat sections each 20 having its opposite ends cut on diverging lines, and its opposite side edges cut on concentric curved lines, the said sections being adapted to be folded and to have their meeting edges overlapped and detachably 25 secured together to provide a frusto-conical shaped marker body, and, when the marker is not in use, to be detached and arranged in superposed relation so as to occupy a minimum amount of space.

30 Other objects will appear and be better understood from that embodiment of my invention of which the following is a specification, reference being had to the accompanying drawing forming a part thereof in 35 which:

Figure 1 is a vertical elevation of the marker,

Fig. 2 is a top plan view thereof,

Fig. 3 is a plan view of the sections, showing 40 both meeting edges secured to each other.

Referring to the drawing in detail, the marker is designated, as an entirety, by the numeral 1, and consists, as shown more particularly in Fig. 3, of a pair of sections 2 45 and 3. These sections 2 and 3 are formed of flexible material, preferably cardboard, paper or any other flexible material, and each has its opposite ends, designated 4, cut on diverging lines and opposite side edges 50 5 and 6 cut on concentric curved lines. The sections 2 and 3 are to be curved transversely and the opposed edges of the sections are adapted to be overlapped, and owing to the configuration of the sections a frusto-conical

body is provided, as shown in Fig. 1. The 55 meeting edges of the sections 2 and 3 are provided with openings 8, which are adapted to receive suitable studs 7, so as to detachably connect the sections to each other. Each section is provided with a plurality of 60 lines 9, which are spaced equidistantly apart, and when the sections are in the formation shown in Figs. 1 and 2, the lines of one section register with the lines of the companion section and form concentric gaging 65 lines.

In use, the person on whom the skirt is to be fitted, stands within the conical shaped body and the skirt to be altered hangs outside of and around the body of the marker. 70 The lines 9 on the body are preferably spaced about one inch apart, and if it is desired that the lower end of the skirt be hung, say two inches from the floor, the lower edge is turned up by the dressmaker 75 to the second line from the bottom of the marker body and then marked, by means of a piece of chalk, completely around the skirt by following the mentioned second line on the marker body. When the marker is not in use, the sections can be detached from 80 each other, and flattened and arranged in superposed relation so as to admit of being stored in a minimum amount of space.

Having thus described my invention what 85 I claim as new, is:

A skirt marker formed of a plurality of 90 flexible, flat sections having their edges cut on concentric curved lines and their ends cut on diverging lines, said sections having a plurality of lines that are parallel with 95 each other and with the curved edges of the sections, one end of one of said sections overlying the adjacent end of the other section, attaching means connecting said end, said overlying end bent at the inner edge of the overlying portion to position the main portions of the sections in alinement, and the free ends of said section adapted for overlying engagement and connection to form a 100 substantially, frusto-conical skirt marker.

In testimony whereof I affix my signature in presence of two witnesses.

ETHEL A. WADE.
